United States Patent Office

Des. 200,743
Patented Mar. 30, 1965

200,743

AIRCRAFT

John J. Grebe, 1505 W. Saint Andrews Drive,
Midland, Mich.

Filed May 9, 1963, Ser. No. 74,830

Term of patent 14 years

(Cl. D71—1)

Fig. 4

Fig. 5

Fig. 3

FIGURE 1 is a top plan view of an aircraft showing my new design;

FIGURE 2 is a top plan view thereof with the rudder member in a raised position;

FIGURE 3 is a side elevational view thereof with the rudder member in a second raised position;

FIGURE 4 is a front elevational view thereof with the rudder member in raised position of FIGURE 2; and

FIGURE 5 is a rear elevational view thereof with the rudder member in raised position of FIGURE 3.

The dominant features of this design reside in the rudder member shown in full lines on the drawing.

I claim:

The ornamental design for an aircraft, as shown and described.
